WRAPPING FOR CIGARETTES

John Walker Chalmers and Donald Richard Patrick Jackson, Deptford, London, England, assignors to Molins Machine Company Limited, London, England, a British company

Original application Sept. 11, 1956, Ser. No. 609,291, now Patent No. 2,922,342, dated Jan. 26, 1960. Divided and this application Feb. 19, 1959, Ser. No. 794,376

1 Claim. (Cl. 221—31)

This invention concerns an improved wrapping for cigarettes, which forms an inner wrapper for a cigarette packet.

The invention provides an inner wrapper for a cigarette packet, which wrapper is formed from two portions of wrapping material, which together enclose a batch of cigarettes, one of the said portions being removable to expose the cigarettes, said wrapper having a pull strip arranged within it so as to be looped loosely beneath some of the said cigarettes, the said pull strip having a free end portion which is adapted to be grasped and pulled in order to lift those cigarettes beneath which the strip is looped, the said free end being concealed by the said removable portion of the wrapper until the said removable portion is removed. Preferably the said removable portion overlaps the other portion adjacent one end of the said batch of cigarettes, and the said free end portion of the pull strip projects from beneath the said other portion so as to lie between the said removable portion and the cigarettes. The said pull strip may be secured to an inner face of the said other portion of the wrapper and extend downwardly from the position at which it is so secured.

A cigarette wrapper in accordance with the invention will now be described by way of example with reference to the accompanying drawings, in which:

Figure 1 is a diagrammatic sectional view,

Figure 2 is a perspective view of the wrapper illustrated in Figure 1,

Figure 3 is a view showing a wrapper similar to that shown in Figure 2 but enclosed in an outer box, and

Figure 4 is a view similar to Figure 2 but showing a removable portion of the wrapper in position before removal.

The wrapper illustrated forms an inner wrapper for a batch of cigarettes, and comprises a metallic foil wrapper 1 which is made in two parts, namely a main portion which envelopes the greater part of the batch of cigarettes, and a removable part 101 which is intended to be discarded when the cigarette package is opened. In Figures 2 and 3 the part 101 is shown as having been removed.

A lifting strip 8, which may be formed of cellophane or like material, is arranged within the foil 1 and is secured to it by adhesive at 100, Figures 1 and 2. The strip 8 extends along the inner surface of the wrapper 1 so as to be looped beneath a few of the cigarettes in the

2

wrapper, and a short length 102 of the strip extends from beneath the edge of the foil 1. This length 102 lies between the top end faces of the cigarettes and the removable part 101 of the wrapping. Thus when the part 5 101 is in place, as shown in Figure 4, the extending length 102 is concealed by the part 101, but when the latter is removed, the part 102 of the strip is plainly visible and easily grasped, as can be seen from Figures 2 and 3.

As shown in Figure 1, the removable part 101 of the wrapping also has a strip 8 secured to its inner surface. This is merely because the wrapping as a whole has been formed from a single piece cut from a web of foil, which piece has the strip 8 secured to it, this composite 10 piece subsequently being subdivided to form the two separate portions of wrapping material which together form the wrapper. The strip 8 is secured to the foil web in the manner described in our co-pending U.S. application Serial No. 609,291, filed September 11, 1956, and in 15 practice it is found convenient to gum the strip 8 over a substantial length so as to ensure that it is secured to the inner surface of the main part of the wrapper.

Figure 3 illustrates a wrapping similar to that shown in Figure 2, and enclosed in an outer cardboard box of 20 rectilinear cross-section which in construction is generally similar to that disclosed in U.S. Patent No. 2,163,828.

This application is a division of our prior application, Serial No. 609,291, filed September 11, 1956, now 25 Patent No. 2,922,342, granted January 26, 1960.

What we claim as our invention and desire to secure by Letters Patent is:

In a package containing cigarettes, an inner wrapper formed of a fixed portion and a removable portion, said 30 removable portion comprising substantially less than one-half of the total wrapper and being before removal arranged in overlapping relationship with the said fixed part at the upper end of the package, so as upon removal to expose the top ends of some of the cigarettes, said 35 wrapper having a lifting strip secured at one end to an inner face of the fixed portion at a position between the top and bottom of the wrapper, said strip extending downwardly along said inner face, extending beneath some of the cigarettes, and extending upwardly along the inner 40 face opposed to said first mentioned inner face, the free end of the lifting strip extending beneath the removable portion of the wrapper and being concealed thereby until the said portion is removed, the said free 45 end portion being, when so exposed, adapted to be grasped and pulled in order to lift the cigarettes beneath which the strip extends.
